UNITED STATES PATENT OFFICE.

DELIA A. CLIMES, OF SAN DIEGO, CALIFORNIA.

WATER-BAG.

1,342,252.

Specification of Letters Patent.

Patented June 1, 1920.

Application filed February 24, 1919. Serial No. 278,646.

To all whom it may concern:

Be it known that I, DELIA A. CLIMES, a citizen of the United States, residing at San Diego, county of San Diego, and State of California, have invented a new and useful Improvement in Water-Bags, of which the following is a specification.

While there is a need and a demand for a water bag which has an opening in the center or elsewhere which will permit of the water-bag being placed over a wound or sore without touching the wound or sore, yet such water-bags as are now constructed and on the market do not permit of their being manufactured cheaply and economically, and sold at a reasonable price, because of their bulky, awkward shape due to their concavo-convex form.

It is the object of my invention to provide a simply-constructed water bag with an opening which will permit of its opening being placed over a wound or sore without touching the same and giving either cold or hot water temperatures to the surrounding tissues, which bag can be made cheaply, packed compactly, sold at a low price and which when empty will occupy much less space than if its form were permanently maintained by its outer wall being more extensive than an inner wall and having these two walls meeting and joining at their edges around the central opening.

In the accompanying drawing, forming a part hereof, Figure 1 is a side elevation in part section showing the bag distended by water, Fig. 2 is the same empty and deflated, Fig. 3 is a top plan and Fig. 4 is a detailed view of a collapsible tube in longitudinal section showing the flanges lying on the walls.

Walls 1 and 2 of my bag are parallel or flat and of the same size and may be of any desired shape. In the center of each wall or elsewhere as may be desired, is an opening 3 of any desired size of the same diameter in each wall. At this opening, wall 1 is attached and fastened to the end of an elastic flexible collapsible tube 4, and wall 2 is fastened to the other end of said elastic flexible collapsible tube 4 of practically the same diameter as the opening in each wall and thus the tube when made of circular shape forms an annular partition around the opening in each wall and extends through the bag and the water therein contained from wall to wall and prevents the

water from escaping through the central opening, so as to permit such opening to be placed over a wound or sore.

This tube 4 may be round or any other desired shape and fastened at each end in any desired manner to the walls 1 and 2. The most desirable method of fastening said tube to the walls, as it now seems, is to make the tube round with an annular shoulder or flange 7 formed in one piece with and attached to the outer circumference of the round tube at each end. This flange being flexible and of waterproof material may be doubled over and passed through the openings in the walls when the bag is being made so that the underneath surface of the flange at each end will lie down on the outside of each wall whereon it may be cemented or otherwise fastened into place so as to provide a watertight annular partition around the central opening and extending through the bag from wall to wall. This tube being also elastic and collapsible is extended when the bag is distended and collapsed when the bag is empty. The opening in the tube must coincide with the opening in the walls so that the tube when fastened to each wall will provide a watertight opening through the bag at all times. The bag may be of any desired shape and form so long as its walls are of the same size and area. Each wall is plaited or lap-seamed with one or more seams 8 running from the central opening to the outer edge of the bag by a seam made by cutting the wall and lapping one edge over to a greater degree at the outer edge than in the center for the purpose of cupping the bag when filled with water and fastening the edges over each other in any desired manner.

When the bag is distended with water this form of construction causes a depression to be formed about the central opening. The size of the depression and the amount of the elevation surrounding it depends on the manner in which the seam is made, that is the amount of the overlapping of the edges and the width of the seam at the outer edge of the bag. This depression enables the walls to remain in such a position as not to touch the wound or sore over which the central opening is placed and at the same time the hollow of such depression tends to conserve the heat and equalize the temperature employed over the tissues to be treated. At the same time such depression is only effec-

tive when the bag is distended and disappears when the bag is empty.

The bag is provided with the usual filling inlet 5 of the ordinary type of construction and this inlet is provided with the usual screw stopper 6.

It is evident that when water is poured into the filling inlet 5, the bag is more or less distended in proportion to the amount

10 of water poured into the bag and wall 1 tends to separate and pull away from wall 2 and the collapsible flexible and elastic tube 4, (to the ends of which walls 1 and 2 are fastened) permits such walls to separate from each other for a distance governed by the amount of water poured into such bag, the length of the tube 4 connecting the two walls and the limit of the stretch in the rubber or other material comprising said tube acting as an elastic annular partition, while the water is held in the bag by the usual screw stopper 6.

When the bag is empty of water, it is evident that the walls will collapse, come 25 together and lie on each other and the central annular partition will also collapse thus permitting the bag to occupy less space and be packed in a flat box and also permit of the bag being made in the ordinary way and thus sold to the user at a 30 very much lower price than those now on the market and thus allow it to be placed within the reach of many more persons needing it than is the case today.

35 Such a bag can be not only used for hot water, cold water or ice and applied to any portion of the body where wounds, sores, boils, inflammations, or lesions of the tissues exist, so as to apply heat or cold to 40 the surrounding tissues without any weight coming on the wound, sore, etc. but on account of the greater distensibility can be used with comfort in place of the usual air-cushions for invalids and for many other 45 purposes not necessary here to specify.

I am aware that water bags having a cen-

tral opening have been heretofore made and likewise those which are of a permanent concavo-convex form due to their being made of the segments of spheres or 50 with an outer wall more extensive than an inner wall and hence do not claim these features but do expressly hereby disavow and disclaim any intention to claim these features as a part of my invention. 55

What I do claim and desire to secure by Letters Patent, is:—

1. A water bag comprising a body of flexible water-proof material having an aperture formed in each of its top and bottom walls, and a collapsible tube secured to said walls and extending through the body of the bag from one of said apertures to the other, said walls being so formed that they will be dished about each end of the tube 65 when the walls are distended.

2. A water bag comprising a body, including top and bottom walls of flexible water-proof material united at their margins and each having an aperture formed 70 therein, each of said walls including a lap-seam produced by cutting the wall from the aperture therein to the margin and lapsing one edge over the other to a greater degree adjacent the margin than adjacent 75 said aperture, and a collapsible tube secured to said walls and extending through the body of the bag from one of said apertures to the other.

3. A water bag comprising a body 80 formed by top and bottom walls of flexible water-proof material united at their margins and each having an aperture therein, and an elastic collapsible tube extending through said body and having its ends secured to the top and bottom walls about the apertures therein, said tube acting to draw 85 said walls toward each other when distended and permitting them to come together throughout their area when the bag 90 is not distended.

DELIA A. CLIMES.
